CLAIM

We claim the ornamental design for a member for translocating roadway markers, as shown and described.

DESCRIPTION

FIG. 1 is a rear perspective view of a member for translocating roadway markers according to the present design;

FIG. 2 is a front perspective view of the member for translocating roadway markers of FIG. 1;

FIG. 3 is a front elevational view of the member for translocating roadway markers of FIG. 1;

FIG. 4 is a rear elevational view of the member for translocating roadway markers of FIG. 1;

FIG. 5 is a top view of the member for translocating roadway markers of FIG. 1;

FIG. 6 is a bottom plan view of the member for translocating roadway markers of FIG. 1; and,

FIG. 7 is a front perspective view of the member for translocating roadway markers of FIG. 1.

The broken lines depict environment subject matter only and form no part of the claimed design.
